Primary Examiner — Clint A Samuel

(57) **CLAIM**

The ornamental design for a lamp as shown and described.

DESCRIPTION

FIG. 1 is a top, front and right side perspective view of a lamp showing my new design;

FIG. 2 is a bottom, front and right side perspective view thereof;

FIG. 3 is a top, rear and left side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of portion 10 in FIG. 3;

FIG. 11 is an enlarged view of portion 11 in FIG. 8; and,

FIG. 12 is an enlarged view of portion 12 in FIG. 5.

The broken lines in the drawings illustrate portions of the lamp which form no part of the claimed design.

1 Claim, 12 Drawing Sheets
